METHOD OF MAKING EQUALIZER SHEETS

Erwin C. Greenway, Chicago, Ill., assignor to Wilson-Jones Company, Chicago, Ill., a corporation of Massachusetts

Application September 25, 1936, Serial No. 102,513

3 Claims. (Cl. 93—1)

This invention relates to a method of applying a plurality of equalizing strips to a sheet to make an equalizer sheet for visible loose leaf binders.

It is an object of this invention to provide a simple, efficient and economical method of simultaneously adhering a plurality of equalizing strips to a sheet in predetermined relationship. Other objects of this invention will become apparent upon reading the following description, taken in conjunction with the accompanying drawings, in which

Figure 1 is a perspective view illustrating the method of positioning the equalizing strips in relation to the sheet to which they are to be affixed;

Figure 2 is a top plan view of the equalizer sheet after the equalizing strips have been adhered to the sheet;

Figure 3 is a top plan view of the equalizer sheet after the equalizing strips have been trimmed;

Figure 4 is a view similar to Figure 1 showing a modified form of equalizing strips;

Figure 5 is a top plan view of the equalizer sheet of Figure 4 after one edge has been trimmed;

Figure 6 is a fragmentary sectional view showing one end of the equalizer sheet before the equalizing strips are trimmed; and

Figure 7 is a fragmentary sectional view showing one end of the equalizer sheet after the equalizing strips have been trimmed.

In the drawings the reference numeral 2 indicates a board or plate member having a pair of positioning bars 3 projecting above the top surface of the plate member 2. The sheet 4 is positioned on the plate member 2 with two of its edges flush with two edges of the sheet. The lower end of the sheet is then raised, as indicated in Figure 1, without moving the main portion of the sheet.

The equalizing strips 5 are formed by recessing a sheet to form a comb like member 6. The sheet 6 may be fabric or paper of any suitable thickness and may be tapered in thickness if desired. The comb like member 6 has a suitable adhesive applied to one surface and is then positioned on the plate member 2 and the raised end of the sheet 4 is then pressed down on the surface of the strips 5 to which adhesive has been applied.

The positioning bars 3 are preferably of substantially the same width as the recess between the adjacent strips 5 and are spaced so as to fit in the two outer recesses of the comb like mem-

ber 6. The distance of the outer positioning bar from the edge of the plate member 2 is sufficient to space the outermost strip 5 inwardly of the outer edge of the sheet 4 a distance sufficient to allow the application of an index tab to the outer edge of the sheet. The positioning bars 3 prevent moving the comb like member 6 too far towards the opposite end of the sheet so that when the sheet 4 is adhered to the comb like member 6 the unrecessed butt portion of the comb like member 6 is spaced from the end of the sheet a distance equal to the thickness of the positioning bars 3.

The sheet 4 is then tumbled and another comb like member 6 is adhered to the opposite end of the sheet. Although it is preferred to secure the equalizing strips at opposite ends of the sheet to opposite surfaces of the sheet, it will be understood that both comb like members may be adhered to the same surface of the sheet.

The sheet 4 is then trimmed along its opposite ends to remove the butt portion of each comb like member 6 and to leave the equalizing strips 5 secured to the ends of the sheet in predetermined spaced relationship. The spaces between the equalizing strips allows flexing of the sheet when it is turned in a loose leaf binder.

The method illustrated in Figures 4 to 7, inclusive, utilizes a comb like member 7 having relatively long strips 8 projecting from one end and relatively short strips 9 projecting from the opposite end. The comb like member 7 is folded along a line spaced from the center before the adhesive is applied to its surface. The sheet 4 is positioned on the plate member just as in the previously described embodiment. The comb like member 7 is positioned as indicated in Figure 4 and the sheet is pressed down on the adhesive on the long strips 8. The short strips 9 are then pressed down against the sheet and the sheet is removed and tumbled to position it for the securing of the other comb like member 7. The sheet is then trimmed to remove the butt portions of the comb like member 7 as in the previous embodiment. It is obvious that the sheet may have equalizing strips applied to only one end of the sheet if desired.

Although I have described two embodiments of my invention in detail, it will be understood that the description thereof is illustrative, rather than restrictive, and many details of the invention may be modified or changed without departing from the spirit or scope of the invention. Accordingly, I do not desire to be restricted to the

exact steps described, except as limited by the appended claims.

I claim:

- 5 1. In a method of making equalizer sheets, the steps of positioning a comb like member adjacent one end of a sheet with the projecting strips of said comb like member projecting into the area of said sheet, adhering said projecting strips to said sheet, and trimming off the butt portion of said comb like member.
- 10 2. In a method of making equalizer sheets, the steps of folding a comb like member having a series of strips projecting from opposite ends,

adhering a sheet between said series of projecting strips, and trimming off the butt portion of said comb like member.

3. In a method of making equalizer sheets, the steps of positioning a folded comb like member adjacent a sheet with spaced strips projecting from opposite ends of said comb like member on opposite sides of said sheet and the butt portion of said comb like member spaced slightly from the end of said sheet, adhering said strips to opposite sides of said sheet, and trimming off said butt portion. 5 10

ERWIN C. GREENWAY.
